US00D478099S

(12) United States Design Patent **(10) Patent No.:** **US D478,099 S**
Muto **(45) Date of Patent:** **** Aug. 5, 2003**

(54) SEWING MACHINE

D462,703 S * 9/2002 Farne D15/69

(75) Inventor: **Hideki Muto**, Tokyo (JP)

* cited by examiner

(73) Assignee: **Janome Sewing Machine Co., Ltd.**,
Tokyo (JP)

Primary Examiner—Mitchell Siegel
(74) Attorney, Agent, or Firm—Niels & Lemack

(**) Term: **14 Years**

(57) CLAIM

(21) Appl. No.: **29/165,241**

The ornamental design for a sewing machine, as shown.

(22) Filed: **Aug. 6, 2002**

DESCRIPTION

(30) Foreign Application Priority Data

Jan. 3, 2002 (JP) 2002-005359

FIG. 1 is a perspective view of the sewing machine of the present invention;

(51) LOC (7) Cl. **15-06**

FIG. 2 is a first side view of the sewing machine of the present invention;

(52) U.S. Cl. **D15/69**

FIG. 3 is a top view of the sewing machine of the present invention;

(58) Field of Search D15/66-72; 112/217.1-217.4,
112/258-262.3

FIG. 4 is a front view of the sewing machine of the present invention;

(56) References Cited

FIG. 5 is a rear view of the sewing machine of the present invention;

U.S. PATENT DOCUMENTS

FIG. 6 is a bottom view of the sewing machine of the present invention; and,

D188,358 S * 7/1960 Garcia D15/69

FIG. 7 is a second side view of the sewing machine of the present invention.

D359,965 S * 7/1995 Nakajima et al. D15/69

1 Claim, 3 Drawing Sheets

D366,490 S * 1/1996 Wu D15/69

D459,369 S * 6/2002 Yamamoto et al. D15/69
